GOLF SCORER

William I. Nicholson, Jr., Tulsa, Okla.

Application May 19, 1947, Serial No. 749,102

1 Claim. (Cl. 235—114)

1
The present invention relates to a new and improved golf score card.

An important object of the invention is to provide a golf score card or the like with means for recording the individual score of any number of players and tabulating the results of competitive play so that the score of the players for each hole as well as the winner of the hole and the points won or lost by the scorekeeper and his partner are readily available upon inspection of the score card.

Other objects and advantages of the invention will become apparent from the following description when taken in conjunction with the accompanying claim and drawings.

Referring to the drawings in which is shown a preferred embodiment of the invention:

Figure 1 is a front view of a score card constructed in accordance with the invention.

Figure 2 is an enlarged detailed front view of the lower portion of the score card shown in Figure 1.

Figure 3 is an enlarged sectional view taken substantially along the line 3—3 of Figure 1.

Figure 4 is a plan view of a token or disc marked to indicate the number of strokes required for a player on each hole.

Figure 4a is an obverse view of Figure 4.

Figure 5 is a plan view of a token marked to indicate the points won or lost by the scorekeeper.

Figure 5a is an obverse view of Figure 5.

Figure 6 is a plan view of a token marked to indicate the names of each of the players of a foursome.

Figure 6a is an obverse view of Figure 6.

Figure 7 is a plan view of a modified form of disc for indicating the score of each player.

Figure 7a is a plan view of a token arranged to be associated with the token shown in Figure 7.

Referring to the drawings in which like numerals indicate like parts in the several views, 10 designates a score card base which may be made of metal, plastic, wood, paper, leather or the like and preferably is of such shape as to be folded or bent transversely along the medial line 11 to form overlapping portions or sections 12 and 13. For the purpose of illustration, the score card 10 is shown made of leather and may be of such size and shape that when folded, it can be inserted into a pocket and may be of simple or fancy design to suit individual tastes. Associated with the inner face of the base 10 and extending transversely of the portions 12 and 13 on opposite sides of the folding line 11, are transversely extending

2
flexible members or strips 14 which may be made of the same material as the base 10 and as shown, are connected at their upper ends by stitching 15 (Fig. 2) to the base, but may be secured by any other suitable means such as adhesive or the like. The members 14 are of such a width that each upper member overlaps its adjacent lower member medially as at 16. In order that the lowermost member 14 in each of the portions 10 12 and 13 may be properly aligned with the adjacent upper members and so that the members 14 will not extend or bulge out too far from the base 10, when the parts are assembled, there may be provided a wedge member 17 (Fig. 3) that is 15 interposed between the base 10 and the lowermost member 14 on each of the foldable portions 12 and 13. The members 14 are arranged in vertical aligned rows and have their inner ends 18 laterally spaced from the adjacent side 19 of the base 20 in order to provide a space 20 between which and the side 19 is a vertical column 21 marked from 1 to 9 inclusive on the portion 12, and 10 to 18 inclusive on the portion 13, for indicating the first and second nine holes of a golf course. The 25 space 20 may be utilized for receiving a card, memo pad or slate or may be divided by the vertical line 22 so as to form a column 23 in which may be inserted the distance of each hole from the tee and a column 24 for inserting the par of 30 each of the holes. The transverse members or strips 14 correspond in number to the number of holes and are in horizontal alignment with adjacent columns 21. Each of the members 14 and 17 is secured at its ends as at 25 to the base 10 by 35 any suitable means such as by vertical stitching, adhesive or the like. The members 14 intermediate their ends are secured to the base at spaced intervals as at 26 so as to separate the same into pockets or compartments 27 (Fig. 3) having 40 closed sides and a closed top but an open lower end portion 28 so as releasably to receive a token or disc insertable in the pocket 27. The lower outer portions of the members 14 which overlap adjacent rows, are formed with spaced cut-out 45 portions 29 positioned in front of each of the compartments 27.
As shown the portions 12 and 13 of the base 10 are divided into four vertical columns 30, 31, 32 and 33 which are identified by the letters A, B, 50 C and D indicating the four players of a foursome, also with a vertical point column 34 and the column 35 for recording the winner of each hole. Arranged to be associated with the columns 30, 31, 32 and 33 are tokens or discs 36 (Fig. 4) which 55 on one side may have printed or otherwise affixed

thereto numbers 3, 4, 5, 6 and X and on its obverse side 37 (Fig. 4a) contains numbers 2, 7, 8, 9 and X. Associated with the point column 34 is a token or disc 38 (Fig. 5) marked plus 1 and plus 2 and minus 1 and minus 2 and X on one side, and on its obverse side 39 (Fig. 5a) marked minus 3 and 4, and plus 3 and 4 and X, or other suitable indicia for indicating points won or lost by the scorekeeper and his partner in a foursome.

In column 35 is arranged to be inserted a disc 40 (Fig. 6) lettered A, B, C and D so as to correspond and identify the four players and indicate the winner of each hole. The obverse side 41 of the disc 40 (Fig. 6a) is shown blank since no additional letters or symbols are required, but may be marked if necessary. Figures 7 and 7a show a pair of complementary or co-acting tokens 42 and 43 arranged to be placed one upon the other and substituted for the token 36 for indicating the score of each player. The token 42 is numbered 2, 3, 4 and 5 and has a cut out V-shaped portion 44, while the token 43 may be numbered 6, 7, 8, 9 and X which numbers are arranged to selectively register with the opening 44 in the disc 42. If, for example, one player scores four the upper token is turned to 4 so as to be visible through its associated window 29. If another player scores six, the upper token is reversed and the lower token is turned to expose the numeral 6 through opening 44 that registers with the window opening 29 in the proper pocket 27, so as to indicate the score of the player. The tokens are of uniform size and shape so as to be conveniently inserted in any one of the pockets 27 and are preferably formed with serrated edges 45 to facilitate their manual rotation in the pockets. Preferably each of the pockets 27 may have associated with it a flat spring 46 (Fig. 2) which extends outwardly from one side of the window 29 so as to engage the outer or serrated surface 45 of the token in the pocket to releasably maintain the same in a fixed position and allow the token to be rotated to move the desired indicia into registration with its associated window opening 29. Circular pockets 47 may be formed in the upper and lower left-hand corners of the portion 12 and 13 of the base to hold three or four extra tokens so as to be available to replace lost or broken tokens. Any suitable means such as the yieldable spring 47' may be used to releasably retain the tokens in the pockets 47. A blank space 48 may be formed in the top of the portion 12 and may contain a pad or slate 49 on which may be written any suitable data. The space 50 between the lower end of the portion 13 of the base and the lowermost member 14 may be used to receive a slate or pad 51 similar to the slate or pad 49. The lower member 17 may overlap the upper edge of the slate 51 and co-act with a ledge or shoulder strip 52 (Fig. 3) on the base for maintaining the slate or pad 51 in position. As will be observed, the transverse members 14 and the formation of the vertical columns in the portion 13 are a continuation of the same columns in the portion 12 and are similarly designated.

The tokens preferably extend sufficiently out from the pockets 27 so as to be easily manipulated by the thumb or fingers. On the pads or slates 49 and 51 may be written any other suitable data.

To illustrate the keeping of the score card, it will be assumed that two points may be won for each hole, one for low ball and one for high ball. The tokens are inserted in their respective pockets before play starts so that a blank portion is ex-

posed through the window openings. If A and B are partners and are paired against C and D, and D is the scorekeeper and the score for each of the first four holes is as indicated in Figure 1, it will be seen that the discs 36 are inserted in the pockets 27 so that they may be rotated to indicate through the openings 29 the score made by each player and will be retained in the pockets by the springs 46 which may be sprung back to permit extraction or insertion of the token and allow the same to be rotated until the proper number registers with the window 29. Since on the first hole D was low with a 3, and C was high with a 5, neither side scored any points so that a disc 38 in the pocket 27 of column 34 of the first hole is turned until the letter X registers with the window to indicate no points or syndicate was won on this hole. Since D was low, a disc 40 in the pocket 27 of column 35 registering with the first hole, is rotated until the letter D on the disc registers with the window. On the second hole all players shoot a 5 so that no points or winner have to be designated. Consequently, the discs 38 and 40 are rotated in their respective pockets in order that the letter X may register through their associated windows. On the third hole C was low with 3 and A was high, C and D win two points. Since D is scorekeeper in column 34 for the third hole, the disc 38 is rotated until plus 2 registers with the window while in column 35, disc 40 is turned so that the letter C will register with the window. On the fourth hole three were tied for low so that disc 40 is rotated in its pocket in column 35, until the letter X is exposed through the window. Since C was high with a 5, A and B win a point and this is indicated in column 34 by disc 38 which exposes a minus 1 through its associated window. As the game proceeds the score and winners of the holes are indicated in columns 34 and 35 so that any player may at any time determine the progress of the game upon inspection of the score card.

The arrangement of the numbering of the discs 36 and 37 may be varied so that a score card may be set up according to the par of the holes and the ability of the players and thus be adapted to a regular foursome without requiring reversal of the tokens. Thus a foursome of low handicap players will use numbers starting with birdies or one under par and ranging to two over par with an X to indicate the ball was picked up or an unusual number of strokes was taken on the hole may be used. For average players the numbering on the disc 36 could start with par and contain five numbers or four numbers and an X. Thus it will be seen that this selective numbering of the disc forms a range adaptive to all players and suitable to a foursome that will require a minimum changing of tokens during a season's play. The tokens may be made of any suitable material and purchased singly or in sets to replace lost tokens or to suit the desires and handicaps of different players. The double tokens shown in Figure 7 may be used when desired and may be of different colors. If a player scores a 4 the upper token is turned to 4 and inserted in the proper compartment. If another player scores a 6 the upper token is turned to the open space and inserted into the proper compartment and the lower token is turned to expose the numeral 6. Likewise, tokens 36 for partners A and B may be red and those for partners C and D may be blue. The tokens 38 for points may also be of different color such as red and blue so that

instead of plus and minus signs the colors may be used to indicate the winners. Thus it will be seen that simple, efficient and accurate means are provided for recording the score of each individual player and the results of competitive play in such a manner that the winners of the game and the points won or lost by the players may be readily determined.

It is to be understood that the forms of the invention shown and described are merely illustrative of preferred embodiments and that such changes may be made as fall within the purview of one skilled in the art without departing from the spirit of the invention and the scope of the claim.

I claim:

A golf scorer comprising a base having transversely extending overlapping members arranged in vertical rows and connected to one face of the base, the transverse members being spaced from one side of the base and extending to the opposite side thereof, means separating each of said members into spaced longitudinally disposed pockets having closed sides, a closed top and an open lower end, the lower ends of the pockets being shaped to form window openings, said pockets being arranged in vertical columns corresponding in number to the number of holes of a golf course, certain of said vertical columns being marked to indicate the names of the players, one of said columns being marked as a point column and another as the winner column, suitably marked tokens or discs insertable in the pockets

identifying the players and having thereon numbers from 2 to 9 inclusive so that upon insertion of a token into one of the player pockets and registering the number on the token corresponding to the number of strokes used by the player for the hole, with the window in the pocket, to indicate the score of the player, said tokens arranged in pairs insertable in said pockets one on top of the other, the top token having a cut-out portion so that a portion of the bottom token is visible thru the cut-out portion, suitably marked tokens or discs insertable in the point pockets for indicating the points won or lost by the score-keeper in playing each hole, and suitably marked tokens having letters or characters representing the names of the players and arranged when a letter or character is inserted in a winner pocket and moved into registration with the window therein, to indicate the winner of the hole.
